VARIABLE PITCH AERIAL PROPELLER

Morris Levine, New York, N. Y., assignor of one-half to Sigmund Einstoss, Brooklyn, N. Y.

Application February 27, 1942, Serial No. 432,581

2 Claims. (Cl. 176—163)

This invention relates to aerial propulsion means and broadly comprehends an improved propeller in which the blades are so constructed and arranged as to exert a greater force than heretofore in proportion to the size of the propeller.

The invention is further directed to an improved aerial propeller of the indicated character wherein the blades are mounted and actuated in a novel manner to vary the pitch thereof, either while the propeller is in operation or at rest.

More particularly the invention is directed to an improved aerial propeller in which the area of the effective surfaces of the blades is materially increased in proportion to the size of the propeller by extending the inner ends of the blades tangentially of the axis of rotation of the propeller rather than radially thereof and inwardly beyond a line tangential to the periphery of the hub.

As a further feature the invention embodies a propeller structure in which the blades thereof are associated with the hub structure for turning movement of the blades on their longitudinal axis with reference to the hub so as to vary the pitch of the blades and wherein means is provided under the control of the pilot for effecting predetermined variations in the pitch of the blades.

With the above enumerated and other objects in view, the invention is set forth in greater detail in the following specification and illustrated in the accompanying drawings in which:

Fig. 1 is a front elevation of an aerial propeller constructed in accordance with the invention.

Fig. 2 is a side view thereof.

Fig. 3 is an enlarged cross sectional view taken approximately on the line 3—3 of Fig. 1.

Fig. 4 is a transverse sectional view taken approximately on the line 4—4 of Fig. 3.

Fig. 5 is a transverse sectional view taken approximately on the line 5—5 of Fig. 3.

Fig. 6 is a perspective of the actuator block as viewed from the top.

Fig. 7 is a perspective view of the actuator block as viewed from the underside.

Referring to the drawings by characters of reference, A designates generally the hub of the propeller which is keyed or otherwise secured to the propeller shaft B for rotation therewith. The hub A is of hollow construction and is provided intermediate its length with a plurality of tangentially disposed bearing bosses 10, two of which are shown in the present embodiment, although the number may be increased to coincide with the number of blades which are to be used so that

the invention is applicable to a two, three or four bladed propeller or even to a greater number of blades or to a single bladed propeller where desired.

5 The propeller blades, which are designated generally by the reference character C, each includes the main body portion 11 and a shank 12 extending inwardly from the body and of reduced diameter with reference thereto so as to define a shoulder 13 at the juncture of the shank with the body. The bearing bosses 10 are of substantially semi-circular configuration throughout the major portion of their length and are provided at their innermost ends with a cylindrical step bearing 14 which surrounds the terminal of the shank 12.

The hub A adjacent the outer end of the boss is also formed with a concave bearing 15 which abuts with the side of the inner extremity of the body to brace the same at the hub. The shank 12

20 of each blade is formed with a reduced threaded stud 16 which extends through an aperture 17 at the inner end of each hub bearing boss 10 and is equipped with a lock nut 18 to retain the blade against axial displacement by centrifugal force,

25 while permitting of turning of the blade on its own axis to vary the pitch of the same. Each of the blade shanks 12 is further provided with helical worm teeth 19 extending generally in the direction of the axis of the blade and disposed

30 inwardly towards the longitudinal axis of the hub A. Under this construction it will be observed that the area of the effective surfaces of the blades is increased in proportion to the size of the propeller as said surfaces extend inwardly 35 beyond the periphery of the hub.

In order to provide means under the control of the pilot for varying the pitch of the blades, a worm gear 25 is secured to a shaft 26 extending longitudinally of the hub and having its longi-

40 tudinal axis coinciding with the axis of the hub and mounted in a bearing web 27 with one terminal 28 of the shaft 26 journaled in a step bearing 29 in the forward end of the propeller shaft B. The worm gear is provided with helical worm

45 teeth 31 which mesh with the worm teeth 19 on the shanks 12 of the blades for simultaneously turning the blades on their own axes to vary the pitch thereof.

In order to impart turning movement to the 50 worm gear 25, the worm shaft 26 has secured to the forward end thereof a cylindrical head 35 which is formed with a helical cam groove 36, within which the cam lug 37 of an actuator block 38 is engaged for effecting turning movement of said head 35. The actuator block 38 is mounted

for guided longitudinal movement in opposite directions in a path parallel to and at one side of the cylindrical head 35 in a guideway 39 fixed to and supported within the hub A, and longitudinal movement thereof is imparted thereto by means of a threaded rotary shaft 40 engaging the threaded bore 41 of the block. The threaded shaft 40 is journaled for rotation and held against axial movement at its opposite ends in the bearing web 27 and a bearing bar 42. The threaded shaft 40 has secured thereto a gear 43 which meshes with the pinion 44 secured to the shaft 45 of a reversible electric motor 46 which is supported in fixed relation to and within the forward part of the hub A. The motor 46 is of the type in which reversing of the polarity effects rotation of the same in opposite directions thereby through the pinion 44 and gear 43 the threaded shaft 40 will be turned in opposite directions to thereby cause the worm gear 25 to turn the propeller blades C in opposite directions of their axes to vary the pitch of the same.

In order to insure the variation of the pitch so as to dispose the same at a plurality of relatively different angles and to place the same under the control of the pilot, manual means is provided for closing the circuit to insure the movement of the actuator block, and automatic circuit breaker means is provided for discontinuing the movement thereof after the predetermined variation in the pitch of the propeller blades has been attained. This is accomplished by arranging the circuit in the following manner:

Conductors 50 and 51 lead from opposite terminals of the motor 46 to a reversing switch 52 and conductors 53 and 54 lead respectively from the reversing switch. The conductor 53 extends to one pole of the source of supply 55, while branch conductors 56 and 57 lead from the conductor 54. The branch conductor 56 extends to one contact 58 of a push button switch S, while the branch conductor 57 is connected in parallel with contact elements 59 and 60. A circuit wire 61 leads from the opposite pole of the source of supply to the contact element 62 of the push button switch S. A circuit wire 63 is connected with the conductor 61 and leads therefrom and is connected in parallel with contact elements 64 and 65. The conductors 53, 56 and 63 which, covered with insulation, extend through the propeller shaft B and are connected to contact rings 66 insulated from each other and from the shaft and which rings are engaged by contact shoes 67 to convey the current to and from the rings to the source of supply and the push button switch S. The reversing switch 52 will be preferably located adjacent the push button switch S within convenient reach of the pilot and this may be accomplished in any desired manner such as leading the wires 50 and 51, 53 and 54, which are covered with insulation, through the propeller shaft and providing rings and contact shoes for controlling the same by remote control.

The contact elements 59 and 64 are arranged in closely spaced relation, as illustrated, while the contact elements 60 and 65 are arranged in closely spaced relation and spaced from the contact elements 59 and 64 with said pairs of contact elements arranged longitudinally of the guideway 39. A bridge piece 70 is mounted adjacent the contact elements 59 and 64 and is carried by a button 71 of insulation material which is normally urged inwardly through an opening in the guideway 39 and into the path of movement of the actuator block 38. A second bridge piece 72

is mounted adjacent the contact elements 60 and 65 and is carried by a button 73 of insulation material which button is normally urged inwardly through an opening in the guideway 39 and into the path of movement of the actuator block. The buttons 71 and 73 are so spaced longitudinally of the guideway and with reference to each other so that when one is engaged by the actuator element, the other is out of engagement therewith.

In use and operation, with the propeller blades set at the angles as shown by the broken line X, the pitch may be varied by the pilot depressing the push button switch S to bridge the contacts 58 and 62. This closes the circuit to the motor 46 as the current will then flow from the right hand pole of the source of supply 55 through the wires 61, contact 62, bridge of the switch S, contact 58, wire 56 to wire 54, thence through the reversing switch 52, wire 51, motor 46, the wire 50 back through the reversing switch to the wire 53 and through wire 53 to the opposite pole of the source of supply. It will, of course, be assumed that the reversing switch 52 has been set to cause the motor 46 to turn in a direction to move the actuator block 38 to the left. The initial movement of the actuator block 38 will cam the button 71 outwardly so that the bridge piece 70 engages contact elements 59 and 64 whereby when the push button is released, the circuit to the motor is then completed from the contact element 59 through the branch wire 57, wire 54, the reversing switch 52, the conductor 51 to the motor, thence from the motor to the wire 50, the reversing switch 52, the wire 53 to one pole of the source 55, thence through the wire 61, the wire 63, to contact element 64, the bridge piece 70 to contact element 59, it being understood that the push button switch is only momentarily depressed to start the motor and move the actuator element until it effects closing of the circuit by the bridge piece 70. The release of the push button switch S breaks the manually controlled circuit and the circuit is then maintained closed as the actuator block is moving to the left. The circuit is then broken automatically as the actuator block moves past the button 71, which is urged inwardly to dispose the bridge piece 70 out of engagement with the contact elements 59 and 64. This movement of the actuator block 38 turns the cylindrical head 35 a partial turn so that the worm gear 25 effects simultaneous turning of the shanks 12 of the propellers to dispose the blades thereof at the angle illustrated by the broken line Y. When the actuator block 38 has moved to the left a sufficient distance to release the button 71 of the bridge piece 70, the block will have been advanced to a point closely adjacent the button 73 of the bridge piece 72. If the pilot desires to further vary the angle or pitch of the propeller to that shown by the broken line Z, he again depresses the push button switch S causing the actuator block 38 in moving further to the left to engage with and force the button 73 of the bridge piece 72 outwardly into engagement with the contact elements 60 and 65 thereby closing the circuit through bridge piece 72 and causing the motor to continue to turn after the push button switch is released until the actuator block 38 releases the button 73 of bridge piece 72 thus automatically breaking the circuit when the pitch or angle of the blades is in the broken line position illustrated at Z.

With the propeller blades set at the angle Z, the operator may change the pitch to that of

either of the angles Y or X by first manipulating the reversing switch 52 and then pressing the push button switch S so as to close the circuit to the motor and causing the same to turn in the reverse direction for moving the actuator element 38 to the right. It will be understood that the initial movement of the actuator element 38 to the right will close the circuit by bridging the contact elements 60 and 65 until the element 38 has passed beyond the button 73 when the circuit will be automatically broken and the propeller blades assume the pitch designated by the broken line angles Y. A second actuation of the push button switch S will cause the actuator element 38 to move further to the right for closing the circuit due to the bridge of the contact elements 59 and 64 with the bridge piece 70.

What is claimed is:

1. In an aerial propeller, a hollow hub, a plurality of blades each having a shank at the inner end thereof provided with worm teeth, means mounting the blade shanks within the hub for turning movement of the blades on their axes to vary the pitch of the same, a worm wheel mounted within the hub to turn with reference thereto on an axis extending longitudinally of the hub with the teeth of the worm wheel engaging the worm teeth of the blade shanks, a rotary head secured to the worm wheel and having a helical cam groove, an actuator block having a cam lug engaging said cam groove, said block being mounted for guided movement in the path parallel to the axis of the rotary head, a feed screw threadedly engaging the actuator block for moving the same in said path of movement, a reversible electric motor connected with the feed screw for turning the same, a circuit including said motor, and a manually operable reversing switch, a normally opened, manually closable

switch for starting the motor, and a switch controlled by the actuator block for maintaining the motor circuit closed for a predetermined period and for automatically breaking the circuit after 5 the actuator block has traveled a predetermined distance so as to effect a predetermined variation in the pitch of the blades.

2. In an aerial propeller, a hollow hub, a plurality of blades each having a shank at the inner end thereof provided with worm teeth, means 10 mounting the blade shanks within the hub for turning movement of the blades on their axes to vary the pitch of the same, a worm wheel mounted within the hub to turn with reference thereto 15 on an axis extending longitudinally of the hub with the teeth of the worm wheel engaging the worm teeth of the blade shanks, a rotary head secured to the worm wheel and having a helical cam groove, an actuator block having a cam lug 20 engaging said cam groove, said block being mounted for guided movement in the path parallel to the axis of the rotary head, a feed screw threadedly engaging the actuator block for moving the same in said path of movement, a reversible 25 electric motor connected with the feed screw for turning the same, a circuit including said motor and a manually operable reversing switch, a normally opened, manually closable switch for starting the motor, and a plurality of 30 switches spaced longitudinally of and in the path of movement of the actuator block and successively engaged thereby upon the initial starting of the motor for maintaining the motor circuit closed for predetermined periods and for automatically 35 breaking the circuit after the actuator block has traveled predetermined distances so as to effect predetermined variations in the setting of the pitch of the blades.

MORRIS LEVINE.
